 The Perfect Circle Company, Hagerstown, Ind.,
 a corporation of Indiana

Application May 25, 1944, Serial No. 537,252

4 Claims. (Cl. 309—13)

1

This invention relates to pistons adapted more particularly for use in internal combustion engines.

The main object of this invention is to provide a light-weight, simple and inexpensive piston which will afford, throughout the operating temperatures and speed ranges of the engine, the most efficient clearance between the piston skirt and the cylinder wall.

More particularly, I provide a piston, having a slotted skirt formed of aluminum alloy or similar light-weight material, with one or more bands of wire wound spirally and tightly around the skirt of the piston to reduce the unconfined diameter of the piston, the wire being formed of a metal having a coefficient of expansion lower than that of the skirt and approximating that of the metal of the engine cylinder. The ends of the wire are secured or anchored to the skirt. My invention eliminates piston skirt collapse, piston slap, excessive wear and scuffing, and also provides better oil control.

Other objects and advantages will become apparent as this description progresses and by reference to the drawing, wherein—

Figure 1 is an elevational view of one form of piston, constructed in accordance with my invention;

Fig. 2 is a similar view of the piston, taken at 90 degrees to Fig. 1;

Fig. 3 is an enlarged detail vertical section, taken on the line 3—3 of Fig. 2; and

Fig. 4 is an enlarged detail horizontal section taken on the line 4—4 of Fig. 3.

The piston is made of an aluminum alloy or a similar metal which is light in weight and has a higher coefficient of expansion than the cast iron or steel wall of the engine cylinder in which it is to operate. I have illustrated the piston as having a head 5 and an integral skirt 6 which is provided with a T-shaped slot 7 consisting of a horizontal slot 7a adjacent the head and a vertical or longitudinal slot 7b extending from the slot 7a to the lower edge of the skirt. The vertical slot 7b is midway between the piston pin bosses, the openings through which are illustrated at 8 in Figs. 1 and 2. The piston, as far as has been described, is of a well-known type but I do not intend to limit my invention thereto, as my invention is adapted for use in any type of piston having a skirt with a longitudinal slot.

Formed in the outer surface of the skirt are grooves, preferably two, one 9 near the top of the skirt and the other 10 near the bottom of the skirt. Each groove is provided with a spiral

2

thread 12. Tightly wound in each spiral thread is a wire 13. Part of the wire in the lower groove is shown broken away in Fig. 1.

In applying each wire band 13 to its groove, one end of the wire is thrust through a round hole 15 (Fig. 3) in the piston skirt at one end of the spiral groove, and the projecting extremity of the wire within the skirt is then bent at right angles, as shown in Fig. 3, to firmly anchor the end of the wire. If desired, the extremity of the wire may first be bent at right angles and then the other end of the wire may be threaded through the hole 15 from the inside of the skirt and the wire drawn through the hole. The wire is then wound under considerable tangential tension or pull in the spiral thread, the tension being such that the force exerted reduces the unconfined diameter of the skirt to its final desired effective diameter. It will be understood that the diameter may be so reduced because of the vertical slot 1b, which is partially closed. By "unconfined diameter," I mean the diameter of the skirt at around room temperatures, after the skirt is slotted and finished but before the wire bands are applied.

In order to anchor the other end of the wire, I provide the skirt at the other end of the spiral thread with a horizontal slot 16. The wire near the end of the last turn is temporarily clamped against movement and then the free terminal of the wire is pushed into the slot, as indicated by the dotted lines 17 in Fig. 3, and then while a pull, as with pliers, is exerted on the terminal, it is bent into a hook around the adjacent end of the slot, as shown in Fig. 3. The clamping means on the wire is then removed, the end of the wire being firmly fastened to the skirt.

Each wire is formed of a metal having a coefficient of expansion lower than that of the metal of the skirt and approximating the coefficient of iron or steel. The wire may be formed of carbon steel and may be similar to that used in musical instruments. I prefer to use a wire having a diameter in the neighborhood of .050 of an inch.

It will be observed that the outer portions of the turns of each band extend slightly, that is, around .005 of an inch, beyond the outer cylindrical surface of the skirt, though, in the broader aspects of my invention, the turns may be flush with this surface or even inset with relation to it.

It is well known that pistons formed of aluminum alloy and the like have a much higher coefficient of expansion than cast iron or steel, of which the cylinder, in which it operates, is formed, and that the slotted skirt tends to collapse, with resultant piston slap, when the engine is cold, and

if rigid enough to resist collapse, the skirt expands and exerts pressure against the cylinder wall, when hot, with resultant excessive wear and scuffing. I have found that with my invention, the skirt, having its unconfined diameter reduced by wire bands, which constantly compress the skirt, the latter may be given sufficient rigidity to prevent collapse when cold, while, at the same time, the wire bands expand and permit the skirt to expand when hot, in substantially the same ratio as the expansion of the cylinder wall, so that the most effective clearance is maintained and undue wear and scuffing are overcome.

With the outer portions of the turns of the wire bands projecting slightly beyond the outer surface 15 of the piston, the bands, in my judgment, form excellent bearings for the skirt against the cylinder wall.

I claim:

1. In a piston for internal combustion engines, 20 a piston skirt provided with a longitudinal slot and formed of metal having a coefficient of expansion higher than that of cast iron or steel, a wire formed of metal having a lower coefficient of expansion than that of the skirt and tightly wound in a series of turns around the slotted portion of the skirt and compressing the skirt to reduce its unconfined diameter to its final effective diameter, and means for fastening the ends of the wire to the skirt.

2. In a piston for use in a cylinder of an internal combustion engine, a piston skirt provided with a longitudinal slot and a circumferential groove and formed of metal having a coefficient of expansion higher than that of cast iron or steel, a wire formed of metal having a lower coefficient of expansion than that of the skirt and tightly wound in said groove in a series of turns around

the slotted portion of the skirt and compressing the skirt to reduce its unconfined diameter to its final effective diameter, with the outer portions of the turns of wire projecting beyond the outer surface of the skirt to provide a bearing adapted to engage the wall of the cylinder, and means for fastening the ends of the wire to the skirt.

3. In a piston for use in a cylinder of an internal combustion engine, a piston skirt provided with a longitudinal slot and a circumferential groove with a spiral thread and formed of metal having a coefficient of expansion higher than that of cast iron or steel, a wire formed of metal having a lower coefficient of expansion than that of the skirt and tightly wound in the spiral thread of said groove in a series of turns around the slotted portion of the skirt and compressing the skirt to reduce its unconfined diameter to its final effective diameter, and means for fastening the ends of the wire to the skirt.

4. In a piston for use in a cylinder of an internal combustion engine, a piston skirt provided with a longitudinal slot and a circumferential groove with a spiral thread and formed of metal having a coefficient of expansion higher than that of cast iron or steel, a wire formed of metal having a lower coefficient of expansion than that of the skirt and tightly wound in the spiral thread of said groove in a series of turns around the slotted portion of the skirt and compressing the skirt to reduce its unconfined diameter to its final effective diameter, with the outer portions of the turns of wire projecting beyond the outer surface of the skirt to provide a bearing adapted to engage the wall of the cylinder, and means for fastening the ends of the wire to the skirt.

RALPH R. TEETOR.
